UNITED STATES PATENT OFFICE

172,495

TYPE FONT

Peter Dom, New York, N. Y., assignor to American Type Founders, Inc., Elizabeth, N. J., a corporation of New Jersey

Original application January 21, 1953, Serial No. 23,203. Divided and this application October 19, 1953, Serial No. 27,215

Term of patent 14 years

(Cl. D64—12)

To all whom it may concern:

Be it known that I, Peter Dom, a citizen of the United States, residing in the city of New York, county of New York, and State of New York, have invented a new, original, and ornamental Design for a Type Font, of which the following is a specification, reference being had to the accompanying drawings, forming part hereof, and in which

The figure is an illustration of a type font showing my new design.

This application is a division of applicant's pending application Ser. No. D.23,203, filed January 21, 1953.

I claim:

The ornamental design for a type font, as shown.
